(57) **CLAIM**

I claim the ornamental design for a shoe sole, as shown and described.

DESCRIPTION

FIG. 1 is a bottom, front, right side perspective view showing a shoe sole according to the invention;

FIG. 2 is a bottom plan view thereof;

FIG. 3 is a left side elevation view thereof;

FIG. 4 is a right side elevation view thereof;

FIG. 5 is a rear elevation view thereof; and,

FIG. 6 is a front elevation view thereof.

The broken lines in the drawings showing the shoe mid-sole and upper, a brand logo tag, tread patterns and portions of the shoe sole illustrate the portions of the design that forms no part of the claim.
